CLAIM

The ornamental design for a combined shelf and hanger rod, as shown and described.

DESCRIPTION

FIG. 1 is a top plan view of a combined shelf and hanger rod, showing our new design;
FIG. 2 is a front elevational view;
FIG. 3 is a right side elevational view;
FIG. 4 is a left side elevational view;
FIG. 5 is a rear elevational view;
FIG. 6 is a bottom plan view;
FIG. 7 is a bottom perspective view; and,
FIG. 8 is a left side elevational view, the broken lines are for environmental purposes only and form no part of the claimed design.

One end of the article is shown broken away to indicate indeterminate length and the hooks are repeated throughout.

FIG. 1.FIG. 2.FIG. 3.FIG. 4.

FIG. 5.

FIG. 6.

FIG. 7.

FIG. 8.
